UNITED STATES PATENT OFFICE.

WASHINGTON A. H. BOGARDUS, OF NEW YORK, N. Y.

RECEIVING APPARATUS FOR TUBULAR TRANSIT SYSTEMS.

SPECIFICATION forming part of Letters Patent No. 669,891, dated March 12, 1901.

Application filed October 23, 1900. Serial No. 34,003. (No model.)

To all whom it may concern:

Be it known that I, WASHINGTON A. H. BOGARDUS, a citizen of the United States, residing at New York, in the county of New York and State of New York, have invented new and useful Improvements in Receiving Apparatus for Tubular Transit Systems, of which the following is a specification.

My invention relates to apparatus for tubular transit systems, and more particularly to receiving apparatus for said systems, and is especially adapted for intermediate stations where it is required not to exhaust the line to the atmosphere at any time; and the object of the present invention is to provide an efficient machine of simple and durable construction designed to operate safely and positively and of such arrangement of coöperating parts as will render the same absolutely reliable. I attain this object in the machine illustrated in the drawings forming a part of this application, in which—

Figure 1 is a longitudinal vertical section of my receiver; Fig. 2, a detail section of excess-pressure-exhaust valve, locking-bolts, operating means therefor, and valve operated thereby; Fig. 3, a vertical cross-section centrally of same, and Fig. 4 a detail section of trip-finger valve.

Referring to the drawings, this machine is adapted to be used in connection with the cushioning-chamber shown in my application, Serial No. 26,493, filed August 10, 1900, a part of which mechanism is shown at the lower left-hand corner of Fig. 1.

1 is a section of incoming transit-pipe or the auxiliary cushioning-chamber mentioned above; 2, an entrance-gate; 3, an exit-gate; 4, a piston-rod carrying said entrance-gate 2; 5, a piston-rod carrying said exit-gate 3; 6, a piston (not shown) fast on said piston-rod 4; 7, a piston fast on said piston-rod 5; 8, a cylinder for said piston 6; 9, a cylinder for said piston 7; 10, the casing of valve for cylinder 8; 11, the casing of valve for cylinder 9; 12, air-pressure-supply pipe for said valves, said valves being substantially alike, said pipe 12 entering chambers 13 in the valve-casings; 14 15, ports leading from opposite ends of the cylinders 8 9 to a valve-barrel 15 in the valve-casings, said valve-barrel 15 being open at

either end into a chamber 16, from which leads the exhaust-pipe 24.

A valve-stem 17 is centrally located in the valve-barrel 15 and carries fast pistons 18 18 55 and also projects through the casings 10 and 11 and carries a flexible diaphragm 22 in a diaphragm-chamber 20 21. The valve-stem 17 also projects clear through the chambers 20 21 and is provided with a knob 23 for 60 hand operation in case of emergency. A spring 19 normally holds the valve-stem 17 and pistons 18 18 in their upward position in valve-casing 11 and is seated on the bottom of the casing 11; but the similar spring 65 performing the same function in valve-casing 10 is seated on the top of the casing 10 and holds the valve-stem 17 and pistons 18 18 in their lower position. A pipe 43 enters the diaphragm-chamber 21 above the diaphragm 70 22, and a pipe 44 enters the diaphragm-chamber 20 below the diaphragm 22. A receiving-chamber 45 is formed between the gates 2 and 3. From the chamber 45 a port 25 leads into a valve-casting 46. In the casting 75 46 is a cylinder 28, in which a valve-piston 26 works, and which piston is seated on a valve-seat 27 in the casting 46 and over port 25. Just above the valve-seat 27 and in the cylinder 28 a port 34 leads to an exhaust-pipe 35. 80 A pressure-balancing pipe 36 enters the cylinder 28 over the valve-piston 26, which pipe 36 leads from the line, thereby admitting the same pressure above the valve-piston 26 as that below the same coming through port 25 85 from chamber 45. The valve-piston 26 is normally held seated by a spring 33, bearing against the top of the casting 46. Fast to the valve-piston 26 is a piston-rod 29, passing through the top of the casting 46 and having 90 a slot 30 in its upper portion. Journaled on a projection of the valve-casting 46 is a hand-lever 31, one end of which engages the slot 30 in the piston-rod 29. A spring 32 normally holds the lever 31 in the position shown in Fig. 2. 95 The slot 30 is of such length that the piston-rod 29 may be raised without encountering the lever 31 when said lever is in its normal position; but when the valve 26 is seated it may be raised by depressing the handle of 100 lever 31, which lever will engage the upper end of the slot 30 and raise the valve 26 against

- the pressure of spring 33, all of which constitutes means for raising said valve by hand. The piston-rods 4 and 5 are preferably extended through the tops of cylinders 8 and 9
- 5 to provide supplemental means for the guidance of the pistons 6 and 7, and the extreme upper end of such projection is provided with a knob 47, which may serve as a means of hand operation in case of emergency.
- 10 A shaft 48 is slidably mounted in the valve-casting 46 and is capable of longitudinal movement. Said shaft 48 is somewhat longer than the distance between the inner faces of the two gates 2 and 3, and for the purpose of bringing its ends as near as possible to the wall of the transit pipe and chamber 45 an angle portion 49 has been applied thereto at either end and rigidly attached to the main shaft by connecting-straps 50 50.
- 15 Upon the shaft 48 are rigidly secured a piston 51, working in a cylinder 52, attached to the valve-casting 46, and a valve-piston 53, having two annular recesses 54 and 55. In the casting of the cylinder 52 is formed a valve-barrel 56, in which works the valve-piston 53. The valve-barrel 56 is provided with a port 57, slightly elongated, which is adapted to communicate, through recess 54, with a port 58 when the valve-piston 53 is in
- 20 its left-hand position and with port 58 through recess 54 and a port 59 through recess 55 when the valve-piston 53 is in its right-hand position. A spring 60, normally holding piston 51, shaft 48, and valve-piston 53 in their right-hand position, is seated against the left-hand end of cylinder 52 and bears against piston 51. A locking-pin 37 is mounted in an aperture in the valve-casting 46 and is adapted to be pushed under valve 26 when the same
- 25 is raised to lock said valve. A piston 38 is fast on said pin 37 and works in a cylinder 39, attached to the valve-casting 46. Said locking-pin 37 projects out of said cylinder 39, and its outer end is provided with a knob 41 for hand operation in case of necessity.
- 30 A spring 40, seated against the outer end of cylinder 39 and bearing against piston 38, normally holds said locking-pin 37 against said valve 26 in position to throw said pin under and lock said valve 26 upon the raising of the same.
- 35 A pipe 43 enters cylinder 39 by a port midway of said cylinder, which is covered by piston 38 when pin 37 bears against valve 26 or is under the same in locking position, but which is uncovered when said pin 37 has been drawn back its full stroke against the pressure of spring 40. A pipe 42 enters cylinder 39 at its extreme left-hand end.
- 40 Just without the gate 3 and chamber 45 a trip-finger 61 is journaled upon a shaft 62, said trip-finger projecting into the path of the outgoing carrier and normally held in such position by a spring 63. The trip-finger 61
- 45 is provided with a spring-pawl 64, having a rigid base-seat 65.
- Above the trip-finger 61 is placed a valve-
- 50 casting 66, in which is a valve-barrel 67. A valve-piston 68 works in said barrel 67 and is provided with an annular recess 69, a lower 70 projecting portion 70, projecting below the casting 66, and an upper projecting portion 71. The barrel 67 is provided with two ports 72 73. The upper projecting portion 71 carries a rigidly-secured flexible diaphragm 74, working 75 in a diaphragm-chamber 75, and the extreme upper end of said upper projecting portion 71 is provided with a hand-knob 76 for hand operation in case of necessity. A pipe 77 enters the diaphragm-casing 75 above the diaphragm 74 and connects with the gate-chamber 78, which communicates at all times with the chamber 45. A balance-pipe 83 enters the casing 75 below the diaphragm 74, which conducts the line-pressure to the chamber below said diaphragm to balance the line-pressure above the same. A pipe 79 enters the diaphragm-casing 75 below the diaphragm 74 and connects with port 57 and a port 80, leading to the left-hand side of the piston 51 in 90 cylinder 52. An exhaust-port 81 connects with port 72 when the valve 68 is in its upper position. The pipe 44 connects with port 58, the pipe 42 with port 59, and pipe 36 and port 73 both with the line air-supply.
- 95 The operation of this device is as follows: The machine in its normal position has the entrance-gate 2 open and exit-gate 3 closed, no pressure being applied to the diaphragms in the casings 20 and 21. A carrier entering 100 from transit-pipe 1 into chamber 45 produces an excess pressure before it which is immediately transmitted through port 25 to valve 26, lifting said valve 26. As valve 26 is raised the locking-pin 37 snaps under it and locks it 105 in its raised position. In this raised position valve 26 exhausts the chamber 45, the entrance-gate 2 having been closed simultaneously with the raising of valve 26 through port 34 and pipe 35 to the atmosphere, coaxing the carrier into the forward end of chamber 45. Simultaneously with the raising of valve 26 the said excess pressure is transmitted through gate-chamber 78 and pipe 77 to the upper side of diaphragm 74, throwing 115 valve 68 down and admitting air-pressure from the line through port 73, recess 69, port 72, pipe 79, port 57, recess 54, and pipe 44 to the under side of the diaphragm 22 in casing 20, throwing the valve in casing 10 against 120 the pressure of its spring and admitting pressure from the line to the top side of the piston in cylinder 8 and closing gate 2. At the same time this action takes place air-pressure is admitted through port 80 from pipe 125 79 to the right-hand side of piston 51, forcing the shaft 48 and its angular portion 49 against gate 2, which is closing. As soon as the gate 2 has entirely closed the shaft 48 jumps above the same, locking it and at the 130 same time admitting pressure from pipe 79 through port 57, recess 55, and pipe 42 to piston 38, withdrawing pin 37 and allowing valve 26 to become seated. When the piston 38 has

been forced back far enough to open the port leading to pipe 43, the air-pressure continues through pipe 43 to the upper side of diaphragm in casing 21, throwing the valve in casing 11 5 and opening gate 3. The carrier then is ejected upon table 82 by air entering through ports in the mechanism mentioned in the previous application, and, in passing out of the chamber 45, encounters and throws up the trip-finger 61, the spring-pawl 64 riding under projection 70 of the valve 68. As the carrier passes beyond the trip-finger 61 said finger is returned to its normal position by the spring 63, the pawl engaging the under side of the 10 projection 70 and forcing the valve 68 to its upper position, cutting off pressure through pipe 79 and exhausting pressure through port 81 from all the valves, allowing the spring for returning each of said valves to return the 15 same to their normal positions, thus closing gate 3 and opening gate 2. It will be seen that as the shaft 48 is longer than the distance between the inner faces of the two gates the spring 60 will exert itself to unlock gate 2, 20 but the shaft 48 will not move farther than the face of gate 3 until that gate is entirely closed, and therefore will not unlock gate 2 until gate 3 is entirely closed, and vice versa. This mechanism absolutely and positively 25 prevents both gates being opened simultaneously and the line exhausted.

It is obvious that various changes in the details and construction of my device may be made without departing from the spirit of my 30 invention.

What I claim, and desire to secure by Letters Patent, is—

1. In tubular transit apparatus, in combination with two gates, a locking and releasing longitudinally-moving rod mounted between said gates and of greater length than the distance between the inner faces of said gates, adapted to simultaneously lock one and release the other of said gates, substantially 45 as described.

2. In tubular transit apparatus, in combination with two gates, a locking and releasing longitudinally-moving rod mounted between said gates and of greater length than the distance between the inner faces of said gates, adapted to simultaneously lock one and release the other of said gates, and a valve operated by said rod, substantially as described.

3. In tubular transit apparatus, in combination with two gates, a locking and releasing longitudinally-moving rod mounted between said gates and of greater length than the distance between the inner faces of said 55 gates, adapted to simultaneously lock one and release the other of said gates and a valve-piston integral with said rod and adapted to be moved therewith, substantially as described.

4. In tubular transit apparatus, in combination with two gates, a locking and releasing longitudinally-moving rod mounted be-

tween said gates and of greater length than the distance between the inner faces of said gates, adapted to simultaneously lock one and release the other of said gates and a piston fast on said rod, and a cylinder for said piston, said rod adapted to be moved by air-pressure admitted to said cylinder and piston, substantially as described.

75

5. In tubular transit apparatus, in combination with two gates, an entrance and an exit gate, a locking and releasing longitudinally-moving rod mounted between said gates and of greater length than the distance between the inner faces of said gates, adapted to simultaneously lock one and release the other of said gates, and a spring normally holding said rod locking said exit-gate, substantially as described.

85

6. In tubular transit apparatus, in combination with an entrance and an exit gate, and pneumatic operating mechanism for said gates and an air-supply, a locking and releasing longitudinally-moving rod mounted between said gates and of greater length than the distance between the inner faces of said gates, adapted to simultaneously lock one and release the other of said gates and a valve operated by said rod opening communication between said air-supply and said exit-gate-operating mechanism when said rod is in position of locking said entrance-gate, substantially as described.

100

7. In tubular transit apparatus, in combination with an entrance and an exit gate, pneumatic operating mechanism therefor and a source of air-pressure supply, of an air-pressure conduit, a main valve in said conduit designed to be opened by excess pressure from a chamber between said gates and closed by a trip-finger mechanism without said exit-gate, an unobstructed air-pressure conduit from said main valve to said entrance-gate-operating mechanism, and an exhaust-port in said main valve for exhausting said latter conduit when said main valve is closed, substantially as described.

105

8. In tubular transit apparatus, the combination with an entrance and exit gate, pneumatic operating mechanism for said gates and an air-supply, of a locking and releasing longitudinally-moving rod mounted between said gates and of greater length than the distance between the inner faces of said gates, a gate-operating supply-pipe communicating with said entrance-gate-operating mechanism, a valve operated by said rod adapted to open communication between said gate-operating supply-pipe and said exit-gate-operating mechanism when said rod is in position of locking said entrance-gate and a valve adapted to open communication between said air-supply and gate-operating supply-pipe when in one position and between said gate-operating supply-pipe and an exhaust-port when in its other position, substantially as described.

115

9. In tubular transit apparatus, the combin-

120

125

130

- nation with a receiving and cushioning chamber, entrance and exit gates therefor, pneumatic operating mechanism for said gates and an air-pressure supply, of a gate-operating 5 supply-pipe communicating with said entrance-gate-operating mechanism, a locking and releasing longitudinally-moving rod mounted between said gates and of greater length than the distance between the inner 10 surfaces of said gates, a valve operated by said rod adapted to open communication between said gate-operating supply-pipe and said exit-gate-operating mechanism when said rod is in position of locking said entrance-gate and closing said communication when in its other position, a trip-finger valve adapted 15 to open communication between said air-pressure supply and said gate-operating supply-pipe when in one position and between said gate-operating supply-pipe and exhaust-port 20 when in its other position, a diaphragm fast to said valve, a casing for said diaphragm, communicating means between said casing and said cushioning-chamber, excess pressure 25 from said cushioning-chamber adapted to throw said valve to the former position, and a trip-finger without said exit-gate adapted to throw said trip-finger valve to the latter 30 position, substantially as described.

10. In tubular transit apparatus, the combination with a receiving and cushioning chamber, an exit-gate therefor, pneumatic operating mechanism for said gate, and an air-supply for said pneumatic operating mechanism, 35 of an excess-pressure-exhaust valve for said receiving-chamber communicating with said chamber, a line-pressure balance-chamber above said valve, a spring for seating said valve, a locking-pin for said valve, a spring 40 normally tending to cause said pin to assume its locking position, a piston fast on said pin, a cylinder for said piston, a pipe leading from the source of air-supply to the innermost part of said cylinder, a pipe leading from the side 45 of said cylinder and covered by said piston when the pin is in locking position, and hand operating mechanism for operating said exhaust-valve and locking-pin by hand, substantially as described.

11. In tubular transit apparatus, the combination with an exit-gate pneumatic operating mechanism and an air-pressure supply therefor and a cushioning-chamber, of an excess-pressure-exhaust valve having a line-pressure balance and a seating-spring, said exhaust-valve communicating with said cushioning-chamber, a locking-pin adapted to lock 55 said exhaust-valve in its open or exhausting position, a piston fast on said locking-pin, a cylinder for said piston, a spring normally holding said pin in its locking position, a port leading from the extreme inner portion of said cylinder to said air-pressure supply, and a port 60 in said cylinder outward of said before-mentioned port and adapted to be covered by said piston when said pin is in its locking position but uncovered when said piston has been 65 withdrawn to its full extent, substantially as described.

12. In tubular transit apparatus, the combination with an entrance and an exit gate and pneumatic operating mechanism therefor of an auxiliary air-pressure supply, a main valve for said supply designed to be opened by excess pressure from a chamber between said gates and closed by a trip-finger mechanism without said exit-gate, an unobstructed air-pressure conduit from said main valve to said entrance-gate-operating mechanism, a locking and releasing bolt for said gates, an air-pressure conduit from said main valve communicating with said exit-gate-operating mechanism, a valve operated by said bolt in said latter conduit designed to admit air-pressure to said exit-gate-operating mechanism when said bolt is in position of locking said entrance-gate, and an exhaust-port in 70 said main valve for exhausting said conduits when said main valve is closed, substantially as described.

13. In tubular transit apparatus, the combination with a receiving-chamber and means for closing the same to the line of an excess-pressure valve for said chamber, an automatic locking-pin for locking said valve in 75 its raised or open position, and pneumatic mechanism for withdrawing or releasing said locking-pin actuated by the complete closure of said means for closing the receiving-chamber to the line, substantially as described.

14. In tubular transit apparatus, the combination with an entrance and an exit gate, a receiving-chamber intermediate said gates, pneumatic operating mechanism for said gates, and a source of air-pressure supply of 80 a main valve designed to be opened by excess pressure from said chamber and closed by a trip-finger mechanism without said exit-gate, a locking-bolt designed to simultaneously lock one and release the other of said 85 gates, an excess-pressure-exhaust valve for said chamber, unobstructed communication between said main valve and said entrance-gate-operating mechanism, an automatic locking-pin designed to lock said excess-pressure-exhaust valve when said valve is raised or 90 opened, pneumatic release mechanism for said locking-pin, an air-pressure conduit between said main valve and said pneumatic release mechanism, a valve in said conduit 95 actuated by said bolt, said valve opened when said bolt is in position for locking said entrance-gate and closed when in its other position, a second conduit leading to said exit-gate-operating mechanism opened to said 100 first conduit by the complete withdrawal or release of said locking-pin and closed by the locking of the same, and an exhaust-port in said main valve designed to exhaust the air-pressure from said gate-operating mechanisms upon the closure of said main valve, 105 substantially as described.

15. In tubular transit apparatus, the combination with an entrance and an exit gate, of a 110

locking and releasing bolt mounted between said gates and of greater length than the distance between the inner faces of said gates, an air-pressure supply, a main valve for said air-pressure supply, automatic means for normally holding said bolt in position for locking said exit-gate, pneumatic mechanism for moving said bolt to its other position, pneumatic mechanism actuated by excess pressure in the chamber between said gates for opening said main valve and a trip-finger mechanism without said exit-gate for closing said valve, unobstructed communication between

said main valve and said pneumatic bolt-moving mechanism, and an exhaust-port in 15 said main valve for exhausting said pneumatic bolt-moving mechanism when said main valve is closed, substantially as described.

In testimony whereof I have signed my name to this specification in the presence of 20 two subscribing witnesses.
